John D. Fine

UNITED STATES PATENT OFFICE.

JOHN D. FINE, OF OKLAHOMA, OKLAHOMA.

CANDY-MAKER'S TABLE.

1,247,101.

Specification of Letters Patent. Patented Nov. 20, 1917.

Application filed April 28, 1917. Serial No. 165,180.

To all whom it may concern:

Be it known that I, JOHN D. FINE, a citizen of the United States, and a resident of the city, county, and State of Oklahoma, 5 have invented new and useful Improvements in Candy-Makers' Tables, of which the following is a specification, reference being had to the accompanying drawings.

This invention is in the art of candy- 10 making, referring more particularly to candy-making tables, wherein heat is maintained for imparting same to the batch of candy to be manipulated.

The object of the invention is to impart 15 heat to the batch to prevent setting or hardening of the same while being worked, and an especial object is to impart heat to the batch at a point remote from the operator, where cool air is most like to strike, and 20 harden that portion of the batch.

Other objects of the invention will appear 25 as the reading of the specification and claims is had.

On the drawing, accompanying and forming 30 a part of the specification, a practical embodiment of the invention is shown, although the structure may be modified, in constructing a table involving the essentials of invention.

On this drawing,

Figure 1 is a plan view of the table,

Fig. 2 is an elevation, partly in section of the same.

Like characters of reference indicate like 35 parts in these figures.

The table is preferable of metal, consisting 40 of a plate 3, from which rises walls 4, 5, 6 and 7, and by which walls are formed air chambers 8 between them and walls 9 and 10, for receiving and radiating the heat from vapor coming from water 11 in the base of the table, contained in a chamber 12 formed by the upper plate 3 and a lower plate 13.

These chambers and walls formed one 45 partition or end wall at each side of the table, and a central partition connecting them, the end walls extending away from the central partition and in opposed direc-

tions. Thus, when this table is located intermediate the ends of an elongated work board or table, the workman on either side of the work table will have a place for his batch upon the heating table, with an end wall and back wall, both heated, so as to 55 keep his batch in workable condition together with the table's heat, so that he can work or spin his batch into products successfully.

Any means of heating, such as a burner 60 14, may be provided, which may be fed in suitable manner as by a feed 15.

In a general way the means for introducing water into the table, and the means for relieving the pressure if there be such when 65 the water boils is indicated in a general way by 16 and 17, one being any form of inlet to be suitable coupled to supply and the other being a suitable form of blow off— 70 so generally known in the art as to require no special illustration.

Likewise a suitable, combined, if desired, thermometer and water gage, indicated in a general way, by 18 may be provided for determining the amount of water in the 75 table, and the temperature of the same.

An important point in this case to be mentioned is the provision of means for providing heat to the bottom, the end not being worked, and the back of the batch 80 being spun into product so that these parts will not harden during operation of the spinning.

Having thus described this invention, I 85 claim:

1. A candy-maker's table, consisting of water containing table, means to heat the water, a vapor receiving and heat radiating wall central of said table and extending upward, and end walls connected thereto on 90 opposite sides and in opposed directions.

2. A candy maker's table, consisting of a water containing table, means to direct water into same, means to heat the water, a vapor receiving and heat radiating wall 95 central of said table and extending upward, end walls associated therewith on opposite sides of the wall and in opposed directions,

means to exhaust excessive pressure, and means to determine the water level and heat generated.

3. A candy-maker's table consisting of a water receiving compartment, means to heat same, means to introduce the water, means to determine its level, means to determine the heat, and means to distribute the heat

above the table along the center of it and along two opposed ends thereof.

10

Signed at Oklahoma, in the county and State of Oklahoma, this 24th day of April, in the year of our Lord, nineteen hundred and seventeen.

JOHN D. FINE.
